UNITED STATES PATENT OFFICE

WILLIAM F. HORSTING, OF WILMETTE, ILLINOIS, ASSIGNOR TO LEATHER EQUIPMENT COMPANY, INC., OF CHICAGO, ILLINOIS, A CORPORATION OF DELAWARE

TENSION FRAME

Application filed August 16, 1930. Serial No. 475,753.

This invention relates to improvements in tension frames as used for the stretching and drying of skins, hides and the like.

The object of the invention is to so form the ⁵ foraminated metal plate to which the hide or skin is toggled for stretching and drying that no portion of the plate will interfere with providing the outer surface of the hide with a smooth and even finish when treating the ¹⁰ hide in the production of the so-called patent leather.

In carrying out the object of my invention, I provide a large opening or cut-away portion ¹⁵ in the plate over which the hide is stretched when toggled to the plate, so that when the hide is pressed inward by the operator when rubbing the hide in pumicing, as well as coating it with enamel, no portion of the plate will be in the way to prevent a ²⁰ smooth and even finish being given to the hide.

In the accompanying drawing,—

Fig. 1 shows a tensioning frame for hide stretching and drying embodying the feature ²⁵ of my invention; and

Fig. 2 is a sectional view of the frame of Fig. 1.

In the drawing, 1 indicates the plate to which the hide is toggled for stretching and drying. The plate is supported within a surrounding frame 2 through the medium of a ³⁰ number of clips 3, 3, which are preferably in the form of straps bent about the frame and riveted or bolted to the plate at the margins thereof as shown.

The plate is foraminated by being provided with a multiplicity of apertures or openings ³⁵ 4 to receive the lugs 5 on the under sides of toggles 6 by which the hide 7 is attached to the plate.

The toggles have upper and lower jaws between which the margin of the hide is clamped. The lower jaw is movable through the medium of a thumb piece at the rear end ⁴⁰ of the toggle, and when the hide is clamped in the jaws, and the toggle hooked in the plate, the hide is supported above and out of contact with the plate, so that air may circulate between the plate and the hide for ⁴⁵ drying the under side thereof as indicated in

Fig. 2. Each toggle has a loop shaped finger piece at its rear end, whereby the operator may handle the toggle, and pull it outward over the plate when stretching and applying a hide thereto.

In accordance with my invention, the plate ⁵⁵ 1 is provided with a large central opening 8 over which the hide extends, and which opening removes from the under side of the hide any portion of the plate to interfere with the hide when it is pressed inward toward the plate during the preparing of the outer surface of the hide as in the making of patent leather. The operator in pressing against the hide when rubbing it, both when pumicing and applying the enamel coating, will naturally flex the hide inward toward the plate and with the opening 8 beneath the plate in the manner shown, the hide will not contact with the plate. The hide is relatively thin and if the plate was continuous under the hide, the perforations in such portion of the plate would allow the hide on contact with the plate to be depressed into the perforations, and thereby produce an uneven ⁶⁰ ⁶⁵ ⁷⁰ ⁷⁵ surface on the outside of the hide, which surface when rubbed by the operator would not receive a continuous and smooth finish as required in the making of patent leather. Thus with my invention the plate does not interfere with the rubbing of the hide and the proper finish may be obtained.

I claim as my invention:

1. A device for stretching and drying hides comprising a foraminated plate to which the side of a hide may be toggled, said plate having a large opening therein, the foraminations along the border of said opening being employed for toggling the hide whereby substantially the whole hide is superposed above the opening and both sides of the hide are accessible for operations involved in treating the hide.

2. A device for treating hides comprising a plate having a plurality of perforations ⁸⁵ ⁹⁰ ⁹⁵ ¹⁰⁰ therein, a large opening in the plate surrounded on all sides by a border containing said perforations, said perforations being arranged so that a hide may be toggled on the frame with substantially the whole of the

hide superposed over the opening, both sides of the hide being accessible for operations involved in finishing the hide, the hide being positioned above the plate, so that it may be
5 pressed within the opening without contacting with the plate.

In testimony whereof I affix my signature.
WILLIAM F. HORSTING.
